UNITED STATES PATENT OFFICE.

WILLIAM C. MOUSER AND JOHN A. SPEAKMAN, OF NEW HOLLAND, OHIO.

COMBINED STOCK RESTRAINING AND DIPPING DEVICE.

1,315,322.

Specification of Letters Patent.

Patented Sept. 9, 1919.

Application filed January 10, 1918. Serial No. 211,231.

To all whom it may concern:

Be it known that we, WILEIAM C. MOUSER and JOHN A. SPEAKMAN, citizens of the United States, residing at New Holland, in 5 the county of Pickaway, State of Ohio, have invented certain new and useful Improvements in Combined Stock Restraining and Dipping Devices; and we do hereby declare the following to be a full, clear, and exact 10 description of the invention, such as will enable others skilled in the art to which it appertains to make and use the same.

This invention is an improvement in apparatus utilized in the care of live stock and 15 has particular reference to a combined restraining and dipping device.

An object of the invention is to provide an improved device of simple and inexpensive construction including means for ringing, 20 altering, washing the stock and removing the horns of cattle.

The inventive idea involved is capable of receiving a variety of mechanical expressions, one of which, for the purpose of illustrating the invention, is shown in the accompanying drawing, wherein:—

Figure 1 is a side elevation of the device constructed in accordance with the invention.

30 Fig. 2 is a top plan view thereof.

Fig. 3 is a bottom plan view of the restraining device or trap.

Fig. 4 is a longitudinal section.

35 Fig. 5 is an elevation of one end of the device.

Fig. 6 is a similar view of the other end of the device showing fragmentarily by dotted lines the hinged side lowered.

Fig. 7 is a perspective view of a strapping 40 or supporting member employed in connection with the invention.

Fig. 8 is a similar view of a nose ring retaining board also used in connection with the device.

45 Fig. 9 is a detail view showing the retaining board in place.

Referring more particularly to the accompanying drawings, the restraining device or trap is shown in what is now believed to be its preferred form and consists of a concrete base 10 upon which is mounted the longitudinal and transverse sills 11 and 12 secured in position by means of bolts 13. Mounted at the ends of the longitudinal 50 sills are the substantially vertical standards 14 and 15 forming a portion of the frame

work of the restraining device, the latter standards being hinged or otherwise pivotally connected to the longitudinal sills as indicated at 16 so that the side of the device 60 of which the standards 15 form a part may be swung downwardly to a horizontal position when desired. The entrance end of the device is formed by a plurality of removable end sections 17 which may be readily removed when it is desired to allow the stock to enter the trap. The top of the device is formed by the spaced planking 18 and at the exit end thereof the same is provided with a pair of adjustable clamping members 70 19 pivoted at 20 and extending in a substantially vertical position with the upper ends thereof projecting beyond the top 18. A transverse and horizontally arranged locking bar or rack 21 is associated with the 75 members 19 and is provided with a plurality of obliquely extending slots or notches 22, the slots on one side of the center of said bar extending in opposite directions from those on the other side. These slots are 80 adapted to receive the free ends of the latch members 23 pivoted at 24 adjacent the upper ends of the members 19 whereby the latter are retained in adjusted positions. One of the members 19 also has pivoted thereto 85 an operating handle 25 and before restraining an animal between these clamping members, the member opposite to which the handle 25 is secured, is first adjusted to any desired position and after the animal's neck 90 is between said bars the handle 25 is then operated to adjust the other member 19 toward the first mentioned member.

When a hog is being restrained, a yoke member 26 is extended transversely of the 95 lower ends of the clamping member 19 and is provided with an opening 27 which receives therein a pin 28 whereby a lateral movement of the member 26 is prevented. In removing the horns of stock a nose fastening member 29 is employed and is also provided in its lower edge portion with an opening 30 for receiving the said pin 28 and said member 29 is provided with an opening 31. In use, the member 29 is substituted for the member 26, 100 shown in Fig. 5, the pin 28 passing through the perforation 30 in the member 29. When the member 29 has been so positioned, gripping tongs, such as are used for grasping the noses of animals may be entered through the 105 opening 31, to grip the nose of an animal, by which operation the animal may be drawn 110

close to the member 29 by withdrawing the tongs through the opening 31. The device for altering the stock comprises a supporting or strapping member 32 having a number of 5 slots 33 therein for receiving the straps 34 which extend through the slots 35 formed in the sides of the restraining device.

Arranged at the entrance end of the restraining device is a chute 36 through which 10 the stock passes before entering the device and having at its inner end an incline 37 which leads upwardly to the bottom of said device.

Embedded in the ground and having one 15 end located beneath the restraining device is a trough or tank 38, preferably made of concrete having at its exit end an incline 39 and at its opposite end beneath the entrance end of the restraining device a chamber 40 for a 20 purpose which will presently appear.

In order to dip or lower the stock into the trough 38, the bottom of the restraining device consists of a rocking platform 41 pivoted at 42 and having depending therefrom at the end thereof adjacent the entrance end of the device, a weight 43 which, 25 when the platform 41 is in its normal or horizontal position, will be located in the chamber 40. The platform 41 is retained in 30 its normal position by means of a locking rod 44 pivoted at 45 to one of the under sides of the longitudinal sills 11, as shown in Fig. 3, and said rod extends under the adjacent end of said platform with the free end thereof 35 projecting through a bracket 45 which limits the movement of said rod in both directions. The free extremity of the rod 44 is provided

with a hook 46 which receives an eye 47 of a push rod 48 connected at its opposite ends to an operating handle 49 pivoted at 50 and actuated to push said rod 48 to swing the locking rod 44 about its pivot and out of engagement with the end of the platform 41 so that the weight of the animal on said platform will tilt the same to an inclined position and 45 thus project the animal into the trough 38.

What is claimed is:—

The combination with a trough of an apparatus of the character described, comprising a frame forming a restraining device and 50 having a side adapted to be opened and closed, a vertically swinging platform mounted in the lower portion of the frame, and adapted at one end to lower into the trough, a lever pivoted to the frame, a latch member mounted on the frame beneath the lowering end of the platform and normally locking the same against lowering movement, connection between the latch member and the lever, means at one end of the frame to 60 clamp an animal within the restraining device, a balancing weight carried by the platform remote from the lowering end thereof to normally hold the same in horizontal position, and means for fastening the frame to 65 the walls of the trough.

In testimony whereof, we affix our signatures in the presence of two witnesses.

WILLIAM C. MOUSER.
JOHN A. SPEAKMAN.
